DESCRIPTION

FIG. 1 is a perspective view of a preferred embodiment of a reclosable container lid of the invention;
 FIG. 2 is a side view of the reclosable container lid of FIG. 1;
 FIG. 3 is a side view of the reclosable container lid of FIG. 1;
 FIG. 4 is a side view of the reclosable container lid of FIG. 1;
 FIG. 5 is a top view of the reclosable container lid of FIG. 1; and,
 FIG. 6 is a sectional view of the reclosable container lid taken along line 6—6 of FIG. 1, showing the contour of the lid.
 The broken lines in the Figures form no part of the claimed design.
 The above statement has been inserted in the specification preceding the claim.
